ABSTRACT

A slipperlike structure with metal toe and rubber sole can be detachably slipped over a light work shoe as a foot protector.

INVENTOR
STEVE PAKULAK

SLIP ON STEEL FOOT GUARD**SUMMARY OF THE INVENTION**

I have devised a slipperlike structure with a metal toe cap and a resilient sole which can be detachably disposed over a lightweight work shoe or the like.

The user can thus avoid the necessity of wearing heavy and expensive work shoes with metal toe caps, and need only carry my invention in pocket or the like for use only as and when needed.

BRIEF DESCRIPTION OF THE DRAWINGS.

In the drawings:

FIG. 1 is a perspective view of my invention;

FIG. 2 is a view taken along line 2—2 in FIG. 1;

FIG. 3 is a view of a modification of my invention; and

FIG. 4 is a view of a part used in the invention of FIG. 2.

DETAILED DESCRIPTION OF PREFERRED EMBODIMENTS

Referring now to FIGS. 1 and 2, a resilient sole 10 formed for example of rubber has a hollow metal toe cap 12 secured on top of the toe portion of the sole. The cap can be formed of steel or tungsten steel for ex-

ample. Steel spring clips 14 extend inclinedly upward from midpoints on opposite sides of the sole to the cap to help hold the shoe 16 of the wearer in place, resting on the sole with the tip in the cap. Ankle straps 18 extending rearward from the cap complete the structure.

As shown in FIGS. 3 and 4, the cap 12 itself can be detachably secured by clips 14A to the shoe 16 by means of removable screws or pins 18. A bracket or tip 20 can be secured to the front of the cap by screw 22 as 10 a further protection.

The arrangement in FIGS. 3 and 4 is suitable for light duty only. Heavier duty applications require use of the structure shown in FIGS. 1 and 2.

While I have described my invention with particular reference to preferred embodiments as shown in the drawings, my protection is to be limited only by the terms of the claims which follow.

I claim:

1. Apparatus for use with a conventional shoe comprising a hollow metal toe cap adapted to detachably receive the toe of a shoe and means detachably securing the cap to the shoe wherein said means includes a resilient sole with the cap secured thereto, and shoe resting on the sole, including spring clips secured to opposite sides of the cap and said clips also secured to said sole.
